[57] **CLAIM**

The ornamental design for a control and meter housing for a battery jumper cable system, substantially as shown and described.

DESCRIPTION

FIG. 1 is a pictorial view of a control and meter housing for a battery jumper cable system showing my new design, the cables and clamps being shown in broken lines for illustrative purposes only;

FIG. 2 is a top view of a second embodiment of my new design;

FIG. 3 is a side view common to both embodiments, the opposite side being identical;

FIG. 4 is a bottom view common to both embodiments; and

FIG. 5 is an end view common to both embodiments, the opposite end being identical.
